Specification for Design.

Patented July 13, 1920.

Application filed November 27, 1918. Serial No. 264,459. Term of patent 14 years.

To all whom it may concern:

Be it known that I, THOMAS BARTON EASBY, a citizen of the United States, residing at Brooklyn, in the county of Kings and State of New York, have invented a new, original, and ornamental Design for Crumb Sets, of which the following is a specification, reference being had to the accompanying drawing, forming part thereof.

In the drawing, Figure 1 is a plan view

and Fig. 2 is a vertical section, showing my new design applied to the tray; Fig. 3 is a plan view and Fig. 4 is a vertical section showing the same design applied to the scraper, the said tray and scraper forming the crumb set of this invention.

I claim:

The ornamental design for a crumb set, as shown.

THOMAS BARTON EASBY.
